UNITED STATES PATENT OFFICE.

JOHN J. BRINKMAN, OF BAKERSFIELD, CALIFORNIA.

WELL-TUBE PERFORATOR.

SPECIFICATION forming part of Letters Patent No. 726,625, dated April 28, 1903.

Application filed March 5, 1903. Serial No. 146,294. (No model.)

To all whom it may concern:

Be it known that I, JOHN J. BRINKMAN, a citizen of the United States, residing at Bakersfield, in the county of Kern, State of California, have invented certain new and useful Improvements in Well-Tube Perforators, of which the following is a specification, reference being had therein to the accompanying drawings.

10 This invention relates to a well-tube perforator, and particularly to a tool having a cutter adapted to be automatically released when the tool has been lowered into the well-casing.

The invention has for an object to provide 15 a perforator-casing having a diagonally-disposed slot in which a cutting-tool is mounted, said tool being normally held at one end of said slot and projected to the opposite end thereof by a coiled spring.

20 A further object of the invention is to improve the construction of the perforator-casing, so that all of the parts of the tool will be protected against injury when being lowered into a well, and also the structure of the cutter to effect a longitudinal movement thereof and also a lateral movement incident to the travel through the inclined slot in the perforator-casing.

Other and further objects and advantages 30 of the invention will be hereinafter set forth and the novel features thereof defined by the appended claims.

In the drawings, Figure 1 is a vertical section through the perforator on line 1 1 of 35 Fig. 2; Fig. 2, a similar section at a right angle to Fig. 1 on line 2 2 thereof; Fig. 3, an elevation of the perforator-casing; Fig. 4, a similar view of the cutting-tool; Fig. 5, a detail perspective of the spring-clasp used in 40 connection with this tool, and Fig. 6 a horizontal section on the line 6 6 of Fig. 1.

Like letters of reference indicate like parts in the several figures of the drawings.

The letter A designates the perforator-casing, which may be of any desired size or configuration desirable for the work to be accomplished. This casing is provided with a longitudinal slot A', extending through the same, and at opposite sides thereof recesses 45 A² are formed, within which the arms B of the carrier for the cutting-tool are adapted to lie. At the lower portion of the casing A a

cylinder A³ is applied in any desired manner and adapted to receive the tension-spring C and protect the same in the use of the tool. 55 This cylinder may be attached to the casing A in any desired manner—for instance, by threading into a socket A⁴, as shown—and the lower end thereof is closed by the head A⁵. The side walls of the lower portion of the 60 casing A are each provided with a slot A⁶, disposed diagonally to a vertical line extending through the casing, and at the base of these side walls a slot A⁷ is formed, through which the lower ends B' of the carrier B are 65 adapted to extend into the cylinder A³. This tool-carrier B has the opposite side arms thereof connected at their lower end by a plate B², from which a depending rod B³ extends, said rod being provided between its ends with a 70 holding-groove B⁴ and at its lower end with a contact-plate B⁵. The portion of the rod B³ beyond the head A⁵ of the cylinder is surrounded by a spring-clasp B⁶, adapted to seat in the groove B⁴ and retain the spring under 75 compression, as shown by dotted-line positions in Figs. 1 and 2. The spring C bears at its lower end upon the surface of the head A⁵ and at its opposite end against an adjustable tension-nut C', threaded upon the rod B³. 80

At the upper end of the arms of the carrier B a suitable cutting-tool is provided, which may be of any preferred character—for instance, a wheel D, having cutting-teeth D', said wheel being mounted upon a pivot-pin 85 D², of suitable strength, which pin passes through the diagonal slots A⁶ and also through the arms of the carrier B. Each of these arms is provided at its pivotal point with a horizontally-disposed slot D³ to permit a lateral movement of the pivot in the arms incident to the lateral travel given the wheel and its pivot by reason of the diagonal slots A⁶. This is necessary, as the cutting wheel or tool is disposed in the slot A' and the carrier moves 90 in a vertical line, so that provision for lateral movement of the wheel must be made.

In the operation of the invention the spring C is placed under tension by compressing the same and held in such position by the spring-clasp upon the rod of the tool-carrier and the perforator then lowered into the well tube or casing to be perforated. When the perforator reaches the bottom of the casing, the con- 95 100

tact-plate bears upon the support there found, and the weight of the perforator-casing and its connected parts forces the spring-clasp from the groove in the rod, thus tripping the 5 spring, which by its expansion throws the cutter-wheel toward the top of the inclined slot and upward against the casing. The perforator is then raised from the bottom of the well to the point where it is desired to 10 form the apertures, and the cutter-wheel rolls against the side of the casing in such upward movement without perforating the same. When the point to be cut has been reached, the tool is again lowered and the 15 tension-spring by holding the wheel in contact with the well-tube permits the weight of the perforator-casing by the inclined-slot connection with the axis of the wheel to force the latter outward through the tube, so that 20 each cutter upon the wheel forms an aperture as it contacts with the tube. When the perforating has been effected, the tube may be raised from the well, as such movement releases the cutting-tool from the tubing. The 25 construction here shown provides a compact tool in which there is little danger of loss of any of the parts, thereby avoiding the labor and expense necessary to remove the tool from the well and recovering the lost parts, 30 while the structure of perforator, in connection with the diagonal slot and spring, produces means for cutting heavy tubes or drive-pipes with holes sufficiently large to permit any desired flow of liquid. The invention 35 also produces a tool simple in construction and easy of operation which can be produced at the minimum expense of manufacture.

It will be obvious that changes may be made in the details of construction and configuration without departing from the spirit of the invention as defined by the appended claims.

Having described my invention and set forth its merits, what I claim, and desire to secure by Letters Patent, is—

45 1. In a perforator, a stock provided with diagonal slots, a cutter-tool mounted in said slots, means for holding said tool at the inner end of said slots, and means for automatically projecting said tool toward the outer 50 end of said slots.

2. In a perforator, a stock provided with diagonal slots, a cutter-tool mounted in said slots, a spring for projecting said tool to the outer end of said slots, and means for retaining said spring under tension.

55 3. In a perforator, a stock provided with diagonal slots therein and a central aperture, a cutting-tool mounted in said aperture by a pivot passing through said slots, a carrier for 60 said tool having arms at opposite sides of said slots connected to said pivot, a rod depending from said arms, and a tension-spring for projecting said arms upwardly.

4. In a perforator, a stock provided with 65 diagonal slots therein and a central aperture, a cutting-tool mounted in said aperture by a pivot passing through said slots, a

carrier for said tool having arms at opposite sides of said slots connected to said pivot, a rod depending from said arms, a tension- 70 spring for projecting said arms upwardly, a protecting-cylinder inclosing said spring and having a head bearing against the lower end thereof, and means for engaging the rod at the opposite face of said head to retain the 75 spring under tension.

5. In a perforator, a stock provided with diagonal slots therein and a central aperture, a cutting-tool mounted in said aperture by a pivot passing through said slots, a 80 carrier for said tool having arms at opposite sides of said slots connected to said pivot, a rod depending from said arms, a tension-spring for projecting said arms upwardly, a protecting-cylinder inclosing said spring and 85 having a head bearing against the lower end thereof, a spring-clasp at the opposite side of said head adapted to engage a groove in said rod, and a contact-plate carried by the free end of said rod. 90

6. In a perforator, a stock provided with diagonal slots therein and a central aperture, a cutting-tool mounted in said aperture by a pivot passing through said slots, a carrier for said tool having arms at opposite 95 sides of said slots connected to said pivot, a rod depending from said arms, a tension-spring for projecting said arms upwardly, a protecting-cylinder inclosing said spring and having a head bearing against the lower end 100 thereof, a spring-clasp at the opposite side of said head adapted to engage a groove in said rod, a contact-plate carried by the free end of said rod, and means at the upper end of said arms for permitting a lateral movement of the pivot-pin therein. 105

7. In a perforator, a stock or casing provided with a central aperture and parallel side walls having diagonal slots therein, a cutting-tool mounted to travel in said slots, 110 a projecting-spring for said tool disposed below said stock, and a cylinder connected to said stock at its upper end and surrounding said spring.

8. In a perforator, a stock or casing having 115 diagonal slots therein, a toothed cutting-wheel pivotally mounted in said slots, carrier-arms for said wheel having horizontal slots at the upper ends thereof to permit a lateral movement of the wheel-pivot therein, 120 a depending rod extending from said arms, and means for projecting said wheel to the outer portion of said diagonal slots.

9. In a perforator, a stock or casing having diagonal slots therein, a toothed cutting-wheel pivotally mounted in said slots, carrier-arms for said wheel having horizontal slots at the upper ends thereof to permit a lateral movement of the wheel-pivot therein, 125 a depending rod extending from said arms, a coiled spring surrounding said rod, a support from said stock bearing against the lower end of said spring, an adjustable nut 130 upon the rod to contact with the upper end

of said spring, and means for retaining said spring under compression.

10. In a perforator, a stock or casing having diagonal slots therein, a toothed cutting-wheel pivotally mounted in said slots, carrier-arms for said wheel having horizontal slots at the upper ends thereof to permit a lateral movement of the wheel-pivot therein, a depending rod extending from said arms, 5 a coiled spring surrounding said rod, a support from said stock bearing against the lower end of said spring, an adjustable nut

upon the rod to contact with the upper end of said spring, a spring-clasp adapted to seat in a groove formed in said rod and to bear 15 against the under face of said support, and a contact-plate carried by the free end of said rod beyond said clasp.

In testimony whereof I affix my signature in presence of two witnesses.

JOHN J. BRINKMAN.
